UNITED STATES PATENT OFFICE

ROBERT C. ALLEN, OF SWARTHMORE, PENNSYLVANIA, ASSIGNOR TO WESTINGHOUSE ELECTRIC & MANUFACTURING COMPANY, A CORPORATION OF PENNSYLVANIA

TURBINE AND CONDENSER UNIT

Application filed February 28, 1931. Serial No. 519,080.

My invention relates to a turbine and condenser construction, and it has for its object to balance the atmospheric pressures on the turbine and on the condenser, so that the condenser may be supported independently of the turbine and connected to the turbine casing by a flexible joint permitting independent expansion and contraction with temperature changes.

10 In accordance with my invention, I dispose two vertical condensers on opposite sides of the turbine exhaust chamber and connect the same thereto by flexible joints. I connect the condensers to each other by tie rods, 15 through which the atmospheric pressures on the condensers are imposed against and neutralize each other.

The above and other objects are effected by my invention as will be apparent from the 20 following description and claims taken in connection with the accompanying drawings, forming a part of this application, in which:

Fig. 1 is an end elevational view of a turbine and condenser unit;

25 Fig. 2 is a plan view showing the turbine, condensers and a generator driven by the turbine; and,

Fig. 3 is a fragmentary elevational view as seen from the line III—III of Fig. 2.

30 Referring now to the drawings more in detail, I show a compound unit comprising a high pressure turbine 10 and a low pressure turbine 11, the motive fluid discharged from the high pressure turbine being conveyed 35 through a receiver pipe 12 to the low pressure turbine. The two turbines drive an electric generator 13. The high pressure turbine 10 is supported on the concrete foundation 14.

The low pressure turbine 11 is disposed 40 over a pit 16 formed in the foundation 14, and a portion of the casing projects down into the pit. The casing is formed with supporting feet 17, shown in Fig. 3, which rest on the foundation 14.

45 The casing of the low pressure turbine 11 includes a fitting 18 which depends from and is rigidly attached to the main portion of the casing. The fitting 18 constitutes an exhaust chamber for conveying the motive fluid 50 exhaust from the low pressure turbine to two

vertical condensers 19 and 20, which are disposed within the pit 16. The fitting 18 is formed with two outlets 21 and 22, which are connected to the inlets 23 and 24 of the condensers 19 and 20 by means of flexible or expansion joints 25 and 26, respectively.

55 The joints may be of any suitable form known in the art, for example, they may consist of heavy sheet rubber. They permit movement relative to the exhaust chamber 18 in any direction. The flexible joints are disposed in parallel vertical planes, and the areas of said planes defined by the flexible joints are preferably equal.

The condensers are rigidly supported on 60 the foundation, independently of the turbine 11. They are shown as mounted on piers 27 resting on the floor of the pit. The condensers are rigidly connected to each other by a plurality of I-beam struts 28, which are 65 bolted at their ends to the respective condensers, as shown in Fig. 3, the struts extend through openings 29 in the foundation 14.

70 The condensers 19 and 20 are constructed 75 in any manner known in the art, for example, as disclosed and claimed in the application of Joseph P. Lidiak, Serial No. 482,881, filed Sept. 18, 1930. Circulating water is supplied through a tunnel 30 in the founda- 80

85 tion.

In operation, the pressure within the exhaust chamber and in the condensing spaces of the condensers is considerably below atmospheric pressure, so that the atmospheric pressure on each condenser on the side opposite the inlet is effective to bias the same in the direction toward the exhaust chamber. By means of the struts 28, however, the atmospheric pressures on the two condensers are imposed against each other, and effects 90 thereof tending to displace the condensers are neutralized.

95 From the above description, it will be seen that I have provided a construction where in the atmospheric pressure on a condenser flexibly connected to an exhaust chamber is counter-balanced by atmospheric pressure in the opposite direction acting on a pressure- neutralizing member and transmitted 100

through struts to the condenser. In the present embodiment, each condenser is a pressure-neutralizing member for the other condenser.

5 While I have shown my invention in but one form, it will be obvious to those skilled in the art that it is not so limited, but is susceptible of various changes and modifications, without departing from the spirit 10 thereof, and I desire, therefore, that only such limitations shall be placed thereupon as are imposed by the prior art or as are specifically set forth in the appended claims.

What I claim is:

15 1. The combination of a turbine casing having an exhaust chamber, a condenser, a flexible joint connecting the condenser to the exhaust chamber, a pressure-equalizing member disposed on the side of the exhaust chamber opposite the condenser, a flexible joint connecting the pressure-equalizing member to the exhaust chamber, the cross-sectional areas of the openings defined by the flexible joints being substantially equal, and means 20 for transmitting the atmospheric pressure on the pressure-equalizing member to the condenser to neutralize the atmospheric pressure on the latter.

2. The combination of a foundation, an 30 elastic fluid turbine casing having an exhaust chamber, said casing being supported on the foundation, a condenser receiving the exhaust from the turbine, a flexible joint connecting the condenser to the exhaust chamber, the condenser being supported on the foundation independently of the turbine casing, a pressure neutralizing member and a flexible joint connecting the same to the opposite side of the exhaust chamber, said 35 member being subjected on its outer side to atmospheric pressure and on its inner side to the absolute pressure within the exhaust chamber, and means for transmitting the atmospheric pressure on the pressure-neutralizing member to the condenser to neutralize the atmospheric pressure on the latter.

3. The combination of a foundation, an 50 elastic fluid turbine casing having an exhaust chamber, said casing being supported on the foundation, a condenser receiving the exhaust from the turbine, a flexible joint connecting the condenser to the exhaust chamber, a pressure-balancing member and a flexible joint connecting the same to the opposite side of the exhaust chamber, the condenser and the pressure-balancing member being supported on the foundation independently 55 of the turbine casing, the pressure-balancing member being subjected on its outer side to atmospheric pressure and on its inner side to the absolute pressure within the exhaust chamber, and a compression member between the condenser and pressure-balancing member for imposing the atmospheric pressures 60

on the condenser and the member against each other.

4. The combination of a foundation, a turbine casing having an exhaust chamber and supported on said foundation, a condenser supported on the foundation independently of the turbine casing, a flexible joint connecting the condenser to one side of the exhaust chamber, a pressure-neutralizing member and a flexible joint connecting the same to the opposite side of the exhaust chamber, said member being subjected on its outer side to atmospheric pressure and on its inner side to the absolute pressure within the exhaust chamber, and struts rigidly tying together the condenser and the pressure-neutralizing member for transmitting the atmospheric pressure on the member to the condenser to neutralize the otherwise unbalanced atmospheric pressure on the latter. 70 75 80

5. The combination of a turbine casing having an exhaust chamber, means for supporting the casing, vertical condensers disposed on opposite sides of the exhaust chamber, flexible joints connecting the condensers to the opposite sides of the exhaust chamber, and connecting members between said condensers for transmitting the force of the atmospheric pressure on either condenser to the other condenser to balance the force of the atmospheric pressure on the latter, and means for supporting the condensers independently of the turbine casing. 90 95

6. The combination of a foundation, a turbine casing supported on the foundation, two vertical condensers disposed on opposite sides of the turbine casing and receiving the exhaust therefrom, said condensers being supported on the foundation independently of the turbine casing, flexible joints connecting the condensers to the opposite sides of the turbine casing, the cross-sectional areas of the connections formed by the flexible joints being substantially equal, and compression members between said condensers through 100 105 110 which the atmospheric pressures on the condensers are imposed against and neutralize each other.

7. The combination of a foundation, a turbine casing supported on the foundation, two vertical condensers disposed on opposite sides of the turbine casing and receiving the exhaust therefrom, said condensers being supported on the foundation independently of the turbine casing, flexible joints connecting the condensers to the opposite sides of the turbine casing, and means for balancing the atmospheric pressures on said condensers against each other comprising struts rigidly connecting said condensers. 115 120 125

8. The combination of a foundation, a turbine casing supported on the foundations, two vertical condensers disposed on opposite sides of the turbine casing and receiving the exhaust therefrom, said condensers being sup- 130

ported on the foundation independently of the turbine casing, flexible joints connecting the condensers to the opposite sides of the turbine casing, the cross-sectional areas of the connections formed by the flexible joints being substantially equal, and means for balancing the atmospheric pressures on said condensers against each other comprising struts rigidly connecting said condensers.

10 9. The combination of a foundation, a turbine casing having an exhaust chamber and supported on the foundation, two vertical condensers disposed on opposite sides of the exhaust chamber and receiving the exhaust therefrom, said condensers being supported on the foundation independently of the turbine casing, flexible joints connecting the condensers to the opposite sides of the exhaust chamber, the cross-sectional areas of the connections formed by the flexible joints being substantially equal, and compression members between said condensers through which the atmospheric pressures on the condensers are imposed against and neutralize each other.

25 10. The combination of a foundation, a turbine casing having an exhaust chamber and supported on the foundation, two vertical condensers disposed on opposite sides of the exhaust chamber and receiving the exhaust therefrom, said condensers being supported on the foundation independently of the turbine casing, flexible joints connecting the condensers to the opposite sides of the exhaust chamber, and means for balancing the atmospheric pressures on said condensers against each other comprising struts rigidly connecting said condensers.

30 11. The combination of a foundation, a turbine casing having an exhaust chamber and supported on the foundation, two vertical condensers disposed on opposite sides of the exhaust chamber and receiving the exhaust therefrom, said condensers being supported on the foundation independently of the turbine casing, flexible joints connecting the condensers to the opposite sides of the exhaust chamber, the cross-sectional areas of the connections formed by the flexible joints being substantially equal, and means for balancing the atmospheric pressures on said condensers against each other comprising struts rigidly connecting said condensers.

35 In testimony whereof, I have hereunto subscribed my name this 27th day of Feb., 1931.

40 ROBERT C. ALLEN.
